UNITED STATES PATENT OFFICE.

ALONZO B. CHOATE AND LOUIS J. PICHA, OF ST. PAUL, MINNESOTA.

AMUSEMENT DEVICE.

1,410,373.

Specification of Letters Patent. Patented Mar. 21, 1922.

Application filed June 18, 1919, Serial No. 305,119. Renewed April 14, 1921. Serial No. 461,368.

To all whom it may concern:

Be it known that we, ALONZO B. CHOATE and LOUIS J. PICHA, citizens of the United States, residing, respectively, at St. Paul, 5 in the county of Ramsey and State of Minnesota, have invented a new and useful Amusement Device, of which the following is a specification.

An object of this invention is to provide 10 an amusement device for children which can be used as a coaster, the parts of said device being arranged to produce greater stability and being selectively positioned and separable so that the device can serve a 15 wider range of usefulness. More particularly the invention is provided with a staff which is arranged back of the forward anti-friction roller or carrier support to produce greater stability. A handle bar is provided 20 and a knee rest, both of which can be selectively and independently positioned at different elevations so as to accommodate the device for use by children of different heights. The invention further is provided 25 with a foot rest and with a device to be used from time to time for carrying packages. With these advantages and other objects in view, our invention comprises the features of 30 construction and combination of parts hereinafter more particularly described and claimed.

In the accompanying drawings forming part of this specification, Fig. 1 is a perspective view of our invention; Fig. 2, is a 35 perspective view of the package receptacle; Fig. 3 is a perspective view of a detail portion of the knee rest; Fig. 4 is a section taken on the plane 4—4—4 of Fig. 1, and Fig. 5 is a section of a detail taken on the 40 plane 5—5—5 of Fig. 1.

In the drawing A indicates the base of the device which resembles a long narrow plate having the single roller 2 journaled below its forward end and a pair of antifriction 45 rollers 3 journaled below its back end, said base being adapted to run upon said rollers when in use. B indicates the front or staff which is substantially vertical although this position is not essential as it may be arranged slightly inclined to the base if it is 50 desired. The lower end of this staff is secured to the base by the brackets 4' and by a tongue and groove connection 5' (see Fig. 5). This staff is mounted back of the forward supporting roller 2 so as to give greater stability to the device when in use

and so that the device will not tip forwardly as if the forward roller support were positioned directly below or back of the staff. Mounted immediately adjoining the lower 60 end of the staff is a horizontal foot support 6, which is in the form of a bar let into the staff by the groove 7 and detachably secured to the staff by the bolt 8. The groove 7 prevents the foot rest from turning on the bolt 65 and co-operates with the bolt in locking the rest firmly on the staff.

Arranged above the foot rest is a knee rest C which resembles a horizontally arranged plate or bar extending rearwardly a 70 short distance from the front above the base, said knee rest being secured to the front by means of a pair of tongues 9, (see Fig. 3), which are adapted to fit closely into one of the pairs of grooves or notches 10 in the 75 front to form a separable and rigid connection. In addition to the connecting means described between the knee rest, and front, a stud 11 is formed on the end of the knee rest between the pair of tongues 9, said stud 80 being adapted to be inserted through the opening 12 in the front adjoining the companion pair of notches 10 in which the knee rest is seated, and a key 13 is inserted through any one of the openings 14 and 14' 85 in the stud on the front side of the staff to lock the knee rest in place. One opening 12 is provided between each pair of notches 10 so that the knee rest and seat can be secured at any selective elevation on the staff. The 90 stud 11 also projects through opening 16 in the wall of a bundle carrier or article receptacle D and the key 13 made to engage the wall of the receptacle through which the stud projects to interlock the receptacle and knee rest and seat on the staff. The opening 14' in the stud 11 is provided so that when desired the bundle carrier D can be removed and the key inserted through said 95 perforation to hold the knee rest firmly on the staff. The wall of the bundle carrier which is perforated to receive the stud 11 is provided with a pair of upright cleats 17 which are adapted to rest along the side edges of the staff to prevent the article receptacle from turning. These cleats are provided with downwardly and rearwardly inclined slots 18 which are adapted to receive pins 19 on the side edges of the staff for the purpose of securing the bundle carrier on the 100 staff independently of the fastening means on the knee rest when desired. Said slots 18

and pins 19 provide a separable coupling means which can be used temporarily and the coupling means on the knee rest provides a more permanent means of attachment. The 5 opening 16 is elongated to admit the end of the stud 11 when the receptacle is hung from the pins 19 irrespective of the position of the knee rest.

Arranged above the knee rest is a horizontal handle bar 20 which may be seated in any one of the series of slots 21 to assist in holding it upon the staff. This handle bar is additionally fastened upon the staff by the removable bolt 22 passing through the 15 handle bar and through a vertical slot 23 in the staff. Thus by positioning the handle bar in any one of the slots 21 and securing it at said selected elevation by means of the bolt 22 the device can be used more readily 20 by children of different heights. The device can also be used by children of different heights due to the selective positioning of the knee rest on the staff. Obviously the knee rest can be used by a small child as a 25 seat while a larger child simultaneously rides and propels the device. The entire structure due to its construction is strong, rigid, durable and inexpensive to produce.

In accordance with the patent statutes 30 we have described the principles of operation of our invention together with the apparatus which we now consider to be the best embodiment thereof but we desire to have it understood that the construction 35 shown is only illustrative and that the invention can be carried out by other means and applied to uses other than those set forth within the scope of the following claims.

40 Having described our invention, what we claim is new and desire to secure by Letters Patent is:

1. An amusement device, comprising, in combination, a base having antifriction carrier rollers arranged below its forward and back ends, a staff mounted upon the forward end of said base at a distance back of the

forward carrying rollers to stabilize the device against tipping forwardly, a handle member upon the upper end of said staff and 50 a knee rest extending backwardly from said staff above said base.

2. An amusement device, comprising, in combination, a base having antifriction carrier elements arranged below its forward 55 and back ends, a staff mounted upon the forward end of said base back of said forward carrying element, a handle member detachably secured to said staff at any one of a number of selective elevations and a knee 60 rest extending backwardly from the staff above said base.

3. An amusement device, comprising, in combination, a base, antifriction carrier elements arranged below the forward and back 65 ends of said base, a staff mounted upon the forward end of said base back of said forward carrying element and having a handle member upon its upper end detachably secured thereto at any one of the number of 70 selected elevations, a foot rest secured to the lower end of said staff, and a knee rest secured to said staff and extending rearwardly therefrom above said foot rest.

4. An amusement device comprising in 75 combination, a base having antifriction carrier elements arranged below its forward and back ends, a staff mounted upon the forward end of said base back of said forward carrying element, said staff having a series 80 of transverse slots and a vertical slot, intercepting said transverse slots, a handle bar adapted to be seated in any one of said transverse slots, a bolt passing through said bar and through said vertical slot to detachably secure the handle bar upon said staff while seated in any one of the transverse 85 slots, a knee rest extending rearwardly from and mounted upon said staff above said base and a bundle carrier detachably mounted 90 upon said staff.

ALONZO B. CHOATE.
LOUIS J. PICHA.
